UNITED STATES PATENT OFFICE.

IRA O. DENMAN, OF TOLEDO, OHIO.

HAND GRIP FOR GOLF CLUBS OR THE LIKE.

Application filed May 4, 1925. Serial No. 27,965.

The invention relates to a hand grip for golf clubs or the like and has for its main object the provision of a grip attachable to a player's hand for assisting in properly holding the handle of the golf club or the like. Another object is the provision of a grip having a portion engageable over a finger of a player's hand and a portion engageable with the handle and arranged to retain the handle against the finger. With these as well as other objects in view the invention resides in the novel features of construction as more fully hereinafter set forth.

In the drawings:—

15 Figure 1 is a perspective view of the hand grip embodying my invention;

Figures 2 and 3 are respectively a perspective view and a side elevation of the grip shown in position.

20 1 is the body of the hand grip for the handle of a golf club or the like. This body preferably has a thickness which gradually increases from one end to the other and is provided with the transverse openings 2 and

25 3 adjacent to each other and located in the end portion of greatest thickness, the openings being respectively engageable over the third and fourth fingers of the player's left hand so that the body lies between the second and third joints of these fingers. The

30 body 1 is also provided with the curved terminal portion 4 at the opposite end, this portion extending approximately parallel to the axes of the openings and having a curvature corresponding approximately to that of the handle of the golf club. The portion of the body forming the outer walls of the openings 2 and 3 is of sufficient extent to assist in maintaining the body substantially

35 at right angles to the portions of the fingers engaged thereby, the arrangement being such that the curved portion of the body engages the handle of the golf club and retains the same against the fingers of a player's

40 left hand and prevents this handle from resting in the palm of the hand.

To assist in holding the hand and particularly the fingers in their proper positions while the player is learning, I have

45 provided the thong 5 which is secured to the end portion of greatest thickness of the body 1 and extends over the back of the hand and is connected by suitable resilient means such as the coil spring 6 to the strap

50 7 which is fastened around the wrist. The arrangement is such that the portions of the

third and fourth fingers between the second and third joints will be maintained more nearly in alignment with the back of the hand so that the correct grip upon the 60 club handle is assured.

From the above description it will be readily seen that I have provided a novel and simple hand grip for the handle of a golf club or the like which provides for 65 retaining the handle against the fingers. It will also be seen that my grip is readily attachable to a player's hand and is so shaped that it will cause no inconvenience. Furthermore, it will be seen that I have provided an 70 auxiliary means for assisting a beginner in holding his hand in the correct position for gripping the club handle.

What I claim as my invention is:

1. A hand grip for a golf club or the like 75 comprising a member attachable to a player's hand and having a portion spaced from the palm of the hand and engageable with the handle to retain the same against the fingers of the hand.

2. A hand grip for a golf club or the like comprising a member engageable over a finger of a player's hand and having a portion spaced from the palm of the hand and engageable with the handle to retain the 85 same against the finger.

3. A hand grip for a golf club or the like comprising a body having a transverse opening therein providing for engagement of the body over a finger of a player's hand 90 and a curved portion upon the body engageable with the hand and arranged to retain the same against the finger.

4. A hand grip for a golf club or the like comprising a body having a transverse opening therein providing for engagement of the body over a finger of a player's hand, a curved portion upon the body engageable with the handle and arranged to retain the same against the finger and means for positioning the body to extend substantially at right angles to the portion of the finger engaged.

5. A hand grip for a golf club or the like 105 comprising a member engageable over a finger of a player's hand and adapted to lie between the second and third joints of the finger, a portion upon the member engageable with the handle and arranged to retain the same against the finger, and means for 110 yieldably holding the portion of the finger between the second and third joints in ap-

proximate alignment with the back of the hand.

6. A hand grip for a golf club or the like comprising a member attachable to a player's hand and having a portion extending transversely of the portion of the hand to which said member is attached, said portion being engageable with the handle and arranged to retain the same against the fingers of the hand.

7. A hand grip for a golf club or the like comprising a substantially rigid member engageable over a finger of a player's hand and having a portion extending transversely of the finger and detachably engageable with the handle to retain the same against the finger.

8. A hand grip for a golf club or the like comprising a member normally carried by a player's hand during the use of the grip and arranged to detachably engage the handle and retain the same against the fingers of the hand.

9. A hand grip for a golf club or the like comprising a substantially rigid member en-

gageable with a finger of a player's hand and having a portion detachably engageable with the handle to hold the same away from the palm of the hand.

10. A hand grip for a golf club or the like comprising a body having a plurality of openings therein providing for engagement of the body over a plurality of fingers of a player's hand and a relatively wide portion upon the body curved to engage the handle and arranged to hold the same away from the palm of the hand.

11. A hand grip for a golf club or the like comprising a body with a thickness greater at one end than the other and having a plurality of transverse openings therein adjacent to the end of greater thickness providing for engagement of the body over a plurality of fingers of a player's hand, and a relatively wide curved terminal portion upon the body engageable with the handle and arranged to retain the same against the fingers.

In testimony whereof I affix my signature.
IRA O. DENMAN.
